UNITED STATES PATENT OFFICE.

RICHARD E. MEYER, OF DETROIT, MICHIGAN.

EXPLOSIVE-ENGINE.

1,252,471.

Specification of Letters Patent. Patented Jan. 8, 1918.

Application filed April 24, 1916. Serial No. 93,047.

To all whom it may concern:

Be it known that I, RICHARD E. MEYER, a citizen of the United States of America, residing at Detroit, in the county of Wayne 5 and State of Michigan, have invented certain new and useful Improvements in Explosive-Engines, of which the following is a specification, reference being had therein to the accompanying drawings.

10 This invention relates to an explosive engine and to an arrangement of the rotary valve mechanism therefor whereby a proper lubrication of the valve is obtained, together with avoidance of leakage and uncertain and 15 noisy operation of the valve mechanism.

The invention consists in the matters hereinafter set forth, and more particularly pointed out in the claim.

In the drawings,

20 Figure 1 is a view partially in section and partially in elevation, of a motor embodying features of the invention;

Fig. 2 is a view in transverse section thereof taken on or about line II—II of 25 Fig. 1;

Fig. 3 is a view in detail of one form of valve;

Fig. 4 is a view in detail of another type of valve;

30 Fig. 5 is a view in detail of a modification of the valve, and

Fig. 6 is a view in detail of a guard ring for securing the valve from deformation.

Referring to the drawings, cylinders 1 are 35 mounted on a suitable engine base 2 in which a crank shaft 3 is mounted in the usual manner. A countershaft 4, that is driven by any preferred type of positively acting mechanism from the main shaft 3 in proper 40 timed relation thereto, operates annular gearing 5 through suitable pinions 6, each gearing being held in axial coincidence substantially with a cylinder by means of an upwardly extending sleeve 7 that rotatably enc-

45 gages in the cylinder and extends at least past inlet ports 8 and outlet ports 9 thereof. Preferably the interior of the annular gears is counterbored to receive the corresponding counterbored end portion of the sleeve with 50 suitable connecting members indicated at 10. That portion of each sleeve which overlaps the ports of the cylinder is likewise ported as indicated at 11 in Fig. 3 and at 12 in Fig. 4, the ports being disposed in numbers according to the speed of the countershaft 4

and the type of engine, either two or four cycle. Whatever the arrangement of parts, the sleeve is longitudinally severed or split through the ports to a transverse segmental cut indicated at 13 lying well below the port 60 of the cylinder. Thus, under the action of the gases in the cylinder while under compression and in explosion, the sleeve tends to hug the cylinder closely and thereby prevents leakage around the ports, being its 65 own packing. Preferably the severed portions with the ports and longitudinal cuts, are formed integrally with the body of the sleeve. The split and ported portion may, however, be split as indicated in Fig. 5 in 70 which case the upper end portion of the cylinder is rabbeted and the split portion correspondingly counterbored, with a stud or groove 14 uniting the parts and securing the split portions between the longitudinal slots 75 so as to permit free expansion and contraction of the ring.

Where the conditions are such that the rings might become deformed, a solid collar 15 with depending flange is dropped into 80 the upper end of the sleeve and prevents excessive yielding of the end portions of the ported part of the sleeve.

In order to provide for sufficient lubrication, a spiral groove 16 is formed on the 85 periphery of the sleeve with a plurality of oil openings 17 therethrough. Pistons 18 of the usual trunk type, ply in the lower portion of the sleeve in the ordinary way through piston rod connections 19 of the 90 crank shaft.

As a result of this construction an engine is obtained having a noiselessly acting rotary valve that effectively prevents leakage around the ports of the cylinders without 95 the necessity of exterior packing rings and that is efficient and positive in action. It is readily machined and assembled with the rest of the motor and forms a most efficient valve mechanism.

100 In the manufacture of the ported valve sleeve, it is preferable to make the walls of the sleeve, at the ported ends thereof, of greater thickness than the remaining walls, and then provide the thick walls with the 105 ports and slits. The entire valve sleeve can then be turned down to a desired size and the ported and slotted end of the valve sleeve will possess a greater degree of resiliency or yieldability than if the sleeve walls were 110

ported and slotted after being turned down or machined to a desired diameter.

What I claim is:—

In an explosive engine, ported cylinders, rotary valve sleeves therein, yieldable end portions at the upper end of each sleeve co-operating in providing ports for each sleeve, and a collar in the upper end of each sleeve

10 preventing excessive yielding of the end portions thereof.

In testimony whereof I affix my signature in presence of two witnesses.

RICHARD E. MEYER.
